UNITED STATES PATENT OFFICE.

FRANZ F. NICKEL, OF EAST ORANGE, NEW JERSEY, ASSIGNOR TO
HENRY R. WORTHINGTON, OF NEW YORK, N. Y., A CORPORA-
TION OF NEW JERSEY.

COMPENSATING DIRECT-ACTING ENGINE.

No. 823,694.

Specification of Letters Patent.

Patented June 19, 1906.

Application filed August 26, 1905. Serial No. 275,858.

To all whom it may concern:

Be it known that I, FRANZ F. NICKEL, a citizen of the United States, residing at East Orange, county of Essex, and State of New Jersey, have invented certain new and useful Improvements in Compensating Direct-Acting Engines, fully described and represented in the following specification and the accompanying drawings, forming a part of the same.

This invention relates generally to that class of direct-acting engines which are provided with one or more compensating or auxiliary cylinders and pistons supplied with a suitable motor fluid and arranged to act in opposition to the main piston or pistons during the first part of the stroke of the engine and in conjunction therewith during the last part of the stroke, thereby permitting the admission of the steam to the main cylinder or cylinders to be cut off before the stroke is completed, while maintaining the proper power of the engine. Such compensating direct-acting engines are well known, and different forms are shown and described in various United States Letters Patent. In such compensating direct-acting engines the engine is liable to make too long or too short a stroke under the varying conditions of use, and the object of the present invention is to provide simple and efficient means for automatically regulating or adjusting the compensating pressure, so as to maintain a practically constant stroke of the engine.

In carrying out the invention an outlet from the compensating system for the escape of fluid to lessen the opposition to the working pressure, and thus increase the effect of the latter, is employed, which is controlled by the length of the engine-stroke in such a manner as to increase the effective compensating pressure in case the stroke shortens and to decrease the compensating pressure in case the engine-stroke lengthens, so as to bring the engine back to normal length stroke in case the stroke varies therefrom, and thus to maintain a practically constant stroke of the engine.

The invention is especially applicable to compensating engines employing an accumulator between the compensating cylinders and source of compensating pressure, and the invention includes certain combinations lim-

ited to such systems; but the broader features of the invention may be applied also to engines in which no such accumulator is employed.

For a full understanding of the invention a detailed description of a construction embodying all the features of the same in their preferred form will now be given in connection with the accompanying drawings, forming a part of this specification, and the features forming the invention will then be specifically pointed out in the claims.

In the drawings, Figure 1 is a diagrammatic side elevation of a vertical pumping-engine of a well-known type embodying the invention, the accumulator being shown in section. Fig. 2 is a plan view of the devices for regulating the compensating pressure. Fig. 3 is a vertical section on the line 3 of Fig. 2. Fig. 4 is a vertical section on the line 4 of Fig. 1 looking to the right. Fig. 5 is a horizontal section on the line 5 of Fig. 3. Fig. 6 is a detail section of the regulating valve and lever looking in the same direction as Fig. 3 and at right angles to Fig. 4.

Referring to said drawings, A is the steam-cylinder; B, the pump-cylinder; C, the force-main; D, the air-chamber on the force-main; E, the engine cross-head; F, the compensating cylinders having their pistons connected to the cross-head, and G the accumulator connected on one side of its piston H to the air-chamber D by pipe I and transmitting pressure to the compensating cylinders F from its smaller piston K through pipe L. The accumulator is shown as of a well-known construction substantially the same as in United States Letters Patent No. 455,935 and No. 628,511, except for the present invention the effective pressure of the piston H being adjusted by admitting air from the working side of the piston H or from a separate supply to the back-pressure tank M, connected by pipe 10 to the back-pressure side of the piston H. As shown, the back-pressure supply is from the working side of the piston H through pipe 11, controlled by a cock 12, so that air may be supplied to the back-pressure side of the piston H through pipe 11, as desired, and the valve 12 then closed.

All the constructions thus far described are old and may be of any other common or suitable form. Referring now to the features

added for the embodiment of the present invention, the back-pressure tank M is provided with an escape-pipe 13, which opens to the atmosphere through a valve controlled by the length of stroke of the engine, so that the back pressure on the accumulator-piston will be increased or diminished as the stroke lengthens or shortens, and the engine-stroke thus be brought back to normal length in case it lengthens or shortens.

The devices for controlling the escape of air from the back-pressure tank M through pipe 13 are as follows: Upon the engine-cradle there is mounted a bracket 14, providing a support for the hinged valve-lever 15, on which moves the weight 16 for adjusting the pressure on the valve 17, which controls the passage 18, connecting the chamber 19, with which pipe 13 connects with chamber 20, opening to the atmosphere through port 1, so that the pressure at which valve 17 will open passage 18 to connect the back-pressure tank M with the atmosphere and allow the escape of air to reduce the back pressure on the accumulator-piston H may be regulated by moving the weight 16 on the valve-lever 15. For moving the weight 16 it is connected by side links 21 to one arm of a bell-crank lever 22, the other arm of which has a pin-and-slot connection with a rod 23, which carries a head 24, engaged by an adjustable tappet 25, mounted on the engine cross-head E. Spring 26 on the rod 23 returns the rod to position on the reversal of the cross-head after the rod has been moved by contact of the tappet 25 with head 24. The weight 16 is adjustable on the links 21 to vary the normal operation of the compensating cylinders by the series of holes, through any of which the links may be bolted to the weight 16.

To secure the slow return of the rod 23 after it has been moved by the tappet 25, while permitting it to be moved quickly by the tappet, the rod 23 carries a piston 27, moving in an oil cataract-cylinder 28, the two ends of which are connected on one side by passage 29 and ports opening to the cylinder, the upper port of which is controlled by spring-pressed check-valve 2 and on the opposite side by passage 30 and ports opening to the cylinder, the lower port of which is controlled by an adjustable needle-valve 3, so that the check-valve 2 opens when the piston 27, with rod 23, is pushed up by the cross-head tappet 55 and lets the oil flow quickly to the other side of the piston through passage 29; but when the spring 26 is returning the piston 27 and rod 23, the check-valve 2 is closed and the oil is forced through the small passage controlled by the adjustable needle-valve, so as to move at the slow rate desired.

The operation of the construction will be understood from a brief description in connection with the drawings. The weight 16 will be adjusted on the lever 15 and the links

21 for the pressure required under normal running conditions, and the tappet 25 on the engine cross-head will be adjusted so that it will strike the head 24 on rod 23 at the end of each engine-stroke of normal length if the rod 23 has then been returned by spring 26, so as to bring the head 24 within reach of the tappet 25. The rod 23 and connected weight 16 on lever 15 are thus kept in such position by the engine while at normal length stroke that the valve 17 will be opened to permit air to be blown off from the back-pressure tank M through pipe 13 only in case leakage past the piston H from the working side to the back-pressure side increases the back pressure beyond that required for the desired stroke of the engine under normal conditions and for which the weight 16 and tappet 25 have been adjusted. If now the engine-stroke lengthens, the tappet 25, by engagement with the head 24, will move the rod 23 farther than in a normal length stroke, which through the lever 22 and links 21 will move the weight 16 outward on the lever 15, so as to increase the pressure on the valve 17, the result being to increase the pressure at which the valve 17 will be opened and air blown off from the back-pressure tank M. The pressure in the back-pressure tank will then be increased gradually by leakage past the piston H from the working side and the pressure in the compensating cylinders gradually reduced to bring the engine back to normal length stroke, the rod 23 being slowly returned to normal position by spring 26, so as to return the weight 16 to normal position at the rate determined by the adjustment of needle-valve 3 to retard the return movement of the piston 27. The tappet 25 will continue to shift the weight 16 outward on the lever 15, so as to increase above the normal the pressure at which the valve 17 will be opened as often as the spring 26 returns the rod 23 and until the normal stroke and operation of the device is resumed. If the stroke of the engine shortens, the head 24 will not be struck by the tappet 25, and the rod 23 will be moved beyond its normal position by the spring 26, and the weight 16 thus shifted inward on the lever 15, so as to reduce the closing pressure on the valve 17 below the normal, with the result that the valve will open against this reduced pressure on the lever, and air thus be blown off from the back-pressure tank M to reduce the pressure on the back-pressure side of the piston H, the pressure in the accumulating cylinders F thus being increased, which will bring the engine back to normal length stroke, when the tappet 25 will again engage the head 24, return the rod 23 and the weight 16, and the normal operation of the devices be resumed.

It will be understood that the invention is not to be limited to the particular arrangement or construction of engine and com-

pensating system shown nor the particular form of the devices illustrated for embodying the invention, but that the invention as defined by the claims may be embodied in constructions of widely different form.

5 What I claim is—

1. In a compensating direct-acting engine, the combination with a compensating system including one or more compensating cylinders and their pistons, of a valve actuated by pressure in the compensating system to control the compensating pressure, and means controlled by the length of the engine-stroke for varying the resistance to movement of said valve to vary the compensating pressure.

10 2. In a compensating direct-acting engine, the combination with a compensating system including one or more compensating cylinders and their pistons and means for applying fluid in opposition to the working pressure to adjust the compensating pressure, of a valve opened by the opposing pressure to permit the escape of opposing fluid, and means controlled by the length of the engine-stroke for varying the resistance to the opening movement of said valve to vary the compensating pressure.

15 3. In a compensating direct-acting engine, the combination with a compensating system including one or more compensating cylinders and their pistons and an accumulator through which the compensating pressure is derived, of a valve actuated by pressure in the compensating system to control the accumulator pressure, and means controlled by the length of the engine-stroke for varying the resistance to movement of said valve to vary the compensating pressure.

20 4. In a compensating direct-acting engine, the combination with a compensating system including one or more compensating cylinders and their pistons and an accumulator through which the compensating pressure is derived, and a back-pressure system for applying fluid to the accumulator-piston in opposition to the working pressure, of an escape-valve on the back-pressure system, and means controlled by the length of the engine-stroke for varying the resistance to opening said valve to vary the compensating pressure.

25 5. In a compensating direct-acting engine, the combination with a compensating system including one or more compensating cylinders and their pistons, of a weighted valve actuated by the pressure in the compensating system to control the compensating pressure, means actuated by the engine-piston for shifting said weight to vary the pressure on the valve, and means for slowly returning the weight when shifted by the engine.

30 6. In a compensating direct-acting engine, the combination with a compensating sys-

tem including one or more compensating cylinders and their pistons, of a weighted valve actuated by the pressure in the compensating system to control the compensating pressure, means actuated by the engine-piston for shifting said weight to vary the pressure on the valve, a spring for returning the weight, and retarding devices for securing a slow return movement of the weight.

70 7. In a compensating direct-acting engine, the combination with a compensating system including one or more compensating cylinders and their pistons, of a weighted valve actuated by the pressure in the compensating system to control the compensating pressure, means actuated by the engine-piston for shifting said weight to vary the pressure on the valve, a spring for returning the weight, a fluid-cylinder having its piston connected to said weight and moved in opposite directions by the engine-piston and the spring, and connections permitting a free circulation of fluid between the opposite ends of the cylinder when the piston is moved by the engine and retarding the circulation when the piston is moved by the spring.

75 8. The combination with a direct-acting engine and its compensating system, of devices for controlling the compensating pressure including a valve, a pressure device acting on said valve, means actuated by the engine-piston for actuating the pressure device to vary the pressure when the length of the engine-stroke is increased, and means for returning the pressure device to normal position.

80 9. The combination with a direct-acting engine and its compensating system, of devices for controlling the compensating pressure including a valve, a pressure device acting on said valve, means actuated by the engine-piston for actuating the pressure device to vary the pressure when the length of the engine-stroke is increased, and means for returning the pressure device to normal position, including retarding devices for securing a slow return movement.

85 10. The combination with a direct-acting engine and its compensating system, of an escape-valve opened by pressure in the system, a weight-lever and shiftable weight controlling said valve, a rod and connections for shifting said weight, a tappet moved by the engine-piston for shifting said rod, a spring for returning the rod, and a cataract-cylinder having a piston connected to said rod and arranged to retard the return movement of the rod.

90 11. The combination with a direct-acting engine and its compensating system, including an accumulator and back-pressure system for adjusting the accumulator pressure, of an escape-valve on the back-pressure system, a weight-lever and shiftable weight controlling said valve, a rod and connections for

shifting said weight, a tappet moved by the engine-piston for shifting said rod, a spring for returning the rod, and a cataract-cylinder having a piston connected to said rod and arranged to retard the return movement of the rod.

In testimony whereof I have hereunto set

my hand in the presence of two subscribing witnesses.
